UNITED STATES PATENT OFFICE.

WALTER J. DUDLEY, OF EVERETT, MASSACHUSETTS, ASSIGNOR TO THE DUDLEY ELECTRIC MANUFACTURING COMPANY, OF CONCORD, NEW HAMPSHIRE.

TRANSMITTING-INSTRUMENT FOR ELECTRIC SIGNALING APPARATUS.

SPECIFICATION forming part of Letters Patent No. 399,505, dated March 12, 1889.

Application filed July 19, 1888. Serial No. 280,361. (No model.)

To all whom it may concern:

- Be it known that I, WALTER J. DUDLEY, of Everett, county of Middlesex, and State of Massachusetts, have invented an Improvement in Transmitting-Instruments for Electric Signaling Apparatus, of which the following description, in connection with the accompanying drawings, is a specification, like letters on the drawings representing like parts.
- 10 This invention is shown embodied in a transmitter or instrument for governing the transmission of electric impulses over a circuit for the purpose of operating individual signaling-instruments or other apparatus of similar nature. The transmitter is especially intended for operating individual signaling-instruments such as shown in Letters Patent 342,340, dated May 25, 1885, there being one such instrument at each of the different stations on a single line, and each instrument having an electro-magnet and actuating-armature operated by successive electric impulses of proper strength and duration to actuate a step-by-step device, and said magnet also controlling a unisoning-armature held in position to arrest the step-by-step device while the actuating-currents are being applied and being retained attracted by residual magnetism between the successive actuating-currents which cause the actuating-armature to vibrate. The said unisoning-armature is so adjusted as to be released or retracted upon the application of rapidly-alternating currents, such as produced by a magneto-electric generator or by a very feeble current of short duration and of opposite polarity to those employed for actuating the step-by-step devices, and the signaling-instrument which is placed in circuit by the step-by-step controlling device at the desired station is also actuated by the alternating or magneto-electric currents, which are, however, not powerful enough to move the step-by-step actuating-armature.
- 15 The transmitting-instrument forming the subject of this invention is adapted to automatically transmit a number of actuating currents or impulses, by which the step-by-step devices of all the signal-controlling instruments on the circuit are moved far enough 20 to bring them to the unison position at which they are arrested by the unisoning-armature, immediately after which the transmitting-instrument causes an alternating magneto-current or feeble battery-current of opposite polarity to the actuating-currents to be sent over the line for a moment and thus effects the release of all the step-by-step devices by the unisoning-armatures, after which the transmitting-instrument sends a definite number of actuating impulses by which all the step-by-step devices are advanced a certain number of steps requisite to place the signaling-instrument at the station to be called in operative condition the said number of steps, placing but one such instrument in circuit at a time after the manner well known to those familiar with individual signaling apparatus. All these currents are caused to be transmitted in the proper number and proper order by a single movement of the operator, who merely turns a crank about once around a dial and stops it opposite a number on the dial corresponding to the station to be called, said movement of the crank actuating and controlling the mechanism of the motor by which the required currents are transmitted, and the whole operation of sending the call being very quickly performed.
- 25 It is desirable for the best operation of signaling-instruments that currents of about the same strength should always be used, and as the different lines of a telephone-exchange are likely to vary widely in resistance, the currents from the same generators or batteries would vary widely in strength in accordance with the well-known laws unless means were provided for preventing such variation.
- 30 The transmitting-instrument forming the subject of this invention contains appliances for evening up the resistance of the different lines with which the instrument may be used, as follows:
- 35 The signaling-instruments and current-generators are properly proportioned to operate with lines of the greatest resistance in the exchange.
- 40 The transmitting-instrument has several resistance-coils which, just before the transmitting part of the instrument is operated, are all in the circuit. The act of turning the

45 50 55 60 65 70 75 80 85 90 95 100

crank to set the transmitter in operation first moves a switch or circuit-changer, by which portions of said resistance are successively removed from the circuit, thereby increasing the strength of a current which is then put on the line. An electro-magnet is included in said circuit, and its armature is properly adjusted to be attracted when the current reaches the proper strength for operating the instruments. The lever of the armature of the said magnet when thus attracted arrests the circuit-changing device by which the resistance-coils are being cut out, and thus retains the proper amount of resistance in circuit until after the signaling-currents have been transmitted.

The invention also consists in many combinations and details of construction, which will be hereinafter described, contributing to the certainty and efficiency of operation of the instruments.

Figure 1 is a front elevation of a transmitting-instrument embodying this invention, a portion of the dial or front frame-plate being broken away to show the parts immediately at the rear of it; Fig. 2, a side elevation of the instrument with a portion of the framework broken away to better show the parts at the rear; Fig. 3, a perspective view of the main shaft of the instrument and parts directly connected therewith; Figs. 4 to 8, various details to be referred to; and Fig. 9, a diagram showing the circuits, current-generators, and various instruments for controlling the circuit and transmission of currents thereof.

The various operative parts are supported on frame-work (shown as consisting of plates a a' a^2 a^3) connected by rods or pillars a^4 , a portion of which are broken away in Fig. 2. The rear plates, a' a^2 a^3 , are smaller than the front plate, a , and may receive a cylindrical casing (indicated in dotted lines at a^5 , Fig. 2) to inclose the working parts. For convenience in reference it may be stated that the devices that directly control the circuit are mainly between the plates a a' , and the mechanism that regulates or governs the movement of said devices is mainly between the plates a' a^2 , and the devices for automatically evening up the resistance of the different lines with which the instrument may be used are mainly between the plates a^2 and a^3 , it being understood that each operator at the central office of the telephone-exchange is provided with one of these instruments, which is switched into or connected with any subscriber's circuit on which a call is to be made in the usual manner.

The front plate or dial, a , (see Fig. 1,) has a portion of its surface graduated and numbered, as shown, the numbers corresponding to the numbers of the stations in any one circuit, and the whole instrument is controlled and operated by a crank, b , which is turned practically once around in the direction of the arrow and brought to the number of the station to be called, where it may be left un-

til another call is to be sent. The said crank b is fixed upon a shaft, b' , (best shown in Fig. 3,) extending from the front plate, a , to the plate a^2 , and at present the mechanism between the plates a^2 and a^3 need not be referred to. The said shaft b' has fixed upon it a disk, c , provided with ratchet-teeth c' , located and spaced with relation to the crank b to correspond with the numbers on the dial a , and being controlled by a pawl, c^2 , pivoted on the front plate, a , as will be understood from Figs. 1 and 2. Thus when the crank b is turned around in the direction of the arrow to any number on the dial, the pawl prevents the reverse rotation of said crank and its shaft. The said shaft b' has loose upon it a sleeve, d , which extends through the plate a' , and at the front of said plate has attached to it the main circuit-controlling disk or wheel e , and at the rear of said plate a' the sleeve d has connected with it a gear, d' , meshing with a train of wheel-work, d^2 d^3 d^4 d^5 , terminating in a regulating device, d^7 , the purpose of which train is merely to retard and control the speed of movement of the disk e when actuated, as will now be described.

The construction of the regulating device is shown in Fig. 4, it consisting of an arm, d^7 , on the most-rapidly moving arbor d^6 of the retarding-train, said arm having at one or both ends a weight, d^8 , pivoted or hung to swing outward under centrifugal force, which may, if desired, be resisted by a spring, d^9 . The weight d^8 turns in a cylinder, d^{10} , and as the speed increases the said weight is thrown outward by centrifugal force, and thus has more friction on the cylinder d^{10} , which prevents further increase of speed. The shaft b' is connected with one end of a spring, f , (see Fig. 5,) the other end of which is connected with the disk e by the pin f^2 , as shown in Fig. 5 and in dotted lines, Fig. 2, so that the rotation of the shaft b' by the crank b , as before stated, strains the said spring, which then tends to rotate the disk e in the same direction, the speed of rotation of said disk being controlled by the train d' d^2 , &c., as before stated. The pawl c^2 , in connection with the teeth c' of the disk c , retains the shaft b' at whatever point it may have been turned to by the operator, thus keeping the spring f strained, so as to propel the disk e until the latter is arrested in its normal position by the stop g g' , which will be hereinafter described.

The crank b may be turned as quickly as possible by the hand of the operator to strain or wind the spring, as just stated, after which the disk e will be rotated in the same direction by the spring f , but at a speed controlled by its regulating-train.

It will be understood that the tension of the spring f tends to rotate the crank b and its shaft in the direction opposite the arrow, and if the said crank should be released by the operator before the disk e was engaged by the pawl c^2 said crank would fly back rapidly and might injure the instrument. To pre-

vent this action, the shaft b' is provided with a gear, b^2 , meshing with a pinion, b^3 , the arbor of which is provided with a retarding device or governor, b^4 , (see Fig. 3,) similar to the one controlling the train $d' d^3$, &c., before described. This governor permits the shaft b' and crank b to be turned as rapidly as the operator readily can by hand; but the said governor retards the crank in case it should fly back in the reverse direction by the action of the spring f sufficiently to prevent injury to the ratchet-teeth c' and pawl c^2 or other parts of the instrument. The disk e is arrested at a definite point, after it has been turned by the spring f , by a locking device, consisting of a pawl or hook, g , (best shown in dotted lines, Fig. 1,) that engages a pin, g' , on the disk e , preventing the rotation of said disk when said hook is in position to engage said pin, as shown in Fig. 1. Below the pin-engaging shoulder the hook has a cam-face, g^2 , which is engaged by a projection, g^3 , on the disk e , when the operator turns the crank b once around from any position in which it may be held by the pawl c^2 , said projection g^3 striking the cam-face g^2 and lifting the hook g , and thus releasing the disk e , which immediately begins to rotate under the stress of the spring f in the same direction that the operator is rotating the crank b , but at a lower speed, owing to the action of the retarding-train, $d' d^3$, &c. The disk e is thus caused to make one complete rotation after the crank b has been turned once around wholly irrespective of the particular point on the dial at which the crank b is stopped.

The stop-hook g has a second stop-hook, g^4 , connected with it that co-operates with a stop-pin, g^5 , on the disk e , as follows: When the said stop-hook g is engaged with its pin g' , the hook g^4 is retained high enough to permit the pin g^5 to pass beneath it, as will be understood from Fig. 1; but after the hook g has been raised and the pin g' has passed it, both hooks g g^4 fall in nearer to the center of the disk e , so that if the crank b were accidentally turned beyond the numbered part of the dial a , so as to begin a second revolution, the pin g^5 would be arrested by the hook g^4 , thus preventing a second revolution of the crank b until after the disk e had made one complete revolution and been arrested in its normal position. When the disk e has nearly finished its revolution from the normal starting-point shown in Figs. 1 and 5, the pin g' engages the under part of the hook-arm g and lifts both hooks g g^4 before it is arrested by the shoulder on the said hook g , and thus provides for the next operation of the crank b .

In order to further prevent danger of over-winding the spring or of running down the said spring in case the shaft b' and parts upon it should be removed from the frame-work, and consequently from the control of the pawl c^2 and locking devices g g^4 , an arm, h , (see Fig. 5,) is pivoted loosely on the shaft b' at the side

of the disk e , and has its movement with relation to said disk limited by stops h' h^2 to about a quarter of a turn. The end of the arm h also stands in the path of the projection g^3 on the disk e , as shown, in such manner as to permit about one turn and a quarter of the disk e with relation to the disk e ; but if in any way the shaft should be turned farther, the pin g^3 would engage the arm h and carry it forward until arrested by the stop h^2 , when the shaft b' can turn no farther without positively carrying the disk e with it. If, on the other hand, the disk e were in any way removed from control of the pawl c^2 , the spring f would tend to rotate the shaft b' backward with relation to the disk e , but in such backward movement the pin g^3 would engage the arm h and carry it along until arrested by the stop h' , when the shaft b' could move backward no farther with relation to the disk e , and consequently the spring f will not be unwound upon such disengagement of the pawl c^2 .

The disk e (best shown in Fig. 5) is the direct-current controlling part of the instrument, and is provided with certain projections which in the rotation of said disk co-operate with circuit-controlling springs or keys to transmit the requisite currents to line.

The actuating currents or impulses by which the step-by-step devices of the signal-controlling instruments are moved are governed by a key or circuit-controlling device, k , (best shown in Fig. 5,) consisting of a lever pivoted at k' and provided with a contact, k^2 , that co-operates with a stationary contact, k^3 , insulated from the frame-work of the machine. The lever k is impelled in the direction to close the contacts by a spring, k^4 , but is moved in the direction to separate the contacts by the projecting parts of the periphery of the disk e . The said disk e is provided with a high projection, e' , that stands under the short arm of the lever k when the said disk is arrested in its normal position, as shown in Figs. 1 and 5, and which then holds the lever k in its most remote position from the contact k^3 and brings another contact-spring, k^5 , connected with said lever into engagement with a contact, k^6 , (see Fig. 1,) insulated from the frame-work of the machine, the purpose of which contacts k^5 k^6 will be hereinafter explained.

When the disk e begins to rotate in the direction of the arrow, Fig. 5, from its normal position, the lever k drops off from the high projection e' and is acted upon by a number of small alternate notches and projections, e^2 , which vibrate the lever with considerable rapidity and thus, by the contacts k^2 k^3 , transmit a number of actuating impulses that bring all the step-by-step devices controlled by the circuit to the unison-point. Beyond the notched part e^2 is a plain part, e^3 , which keeps the lever k , with the contacts k^2 k^3 , separated, and while this part e^3 of the disk is in engagement with the lever k the projection e' passes over the spring m , which transmits the current by

which the unisoning-armature is operated to release the step-by-step device. After the projection e' has passed the spring m and the plain part e^3 of the disk has passed the lever k , a number of large notches and projections, e^4 , (see Fig. 1,) arrive in position to actuate the lever k and contacts $k^2 k^3$, by which a number of comparatively-slow impulses are transmitted, that actuate the step-by-step devices 10 in unison with great certainty, thus advancing them to the desired point to place the instrument at the station to be called in operative condition. A sufficient number of large notches e^4 are provided to advance the step-by-step device as far as may be required to bring the signaling-instrument at any station into operative condition; but only a certain number of said notches e^4 are permitted to operate on the key k at any time, 15 the said number being determined in accordance with the position to which the lever b was turned on the dial a , as follows: A loose cam-segment, n , is pivotally connected at n' with the disk e , and has its other end controlled by a pin, n^2 , on said disk, which permits the movement of said segment n between the position shown in full and dotted lines, Fig. 5. In the dotted-line position the said segment n permits the notches e^4 to act on the 20 lever k , but in the full-line position the said segment n engages the lever k , which is wide enough for this purpose, and thus retains the said lever stationary in the same position that it is held by the unnotched part e^3 of the 25 periphery of the disk e . This segment is controlled by the pin g^3 on the disk e , which raises the segment to the full-line position shortly after its pivoted end n' has passed the said pin g^3 , and thus the position of the pin 30 g^3 , which depends on the position to which the crank b is turned and held by the pawl c^2 , determines the time in the rotation of the disk e that the segment is thrown out and the lever k removed from control of the teeth e^4 . 35 For example, as shown in the drawings, the crank b is stopped opposite the number 6 on the dial, and in this position six of the notches e^4 will pass by the lever k and cause six vibrations thereof before the segment n is 40 thrown out by the pin g^3 , and the vibration of the lever k thus stopped.

If the crank b had been stopped opposite number 1, the segment would have been thus thrown out after the first notch had passed and 45 acted on the lever k , and if turned to any other number on the dial the said segment would be thrown out after the same number of notches had passed the lever k . Beyond the large notches e^4 the disk e has a plain portion, e^5 , 50 which retains the key k with the contacts $k^2 k^3$ separated, and at this time a number of projections, e^6 , (see Fig. 2,) at the rear side of the disk e^5 , co-operate with a spring, m' , by which the circuit is closed between the line 55 and the magneto-generator and the magneto-electric currents thus transmitted, which ring the bell in that station in which the said bell

has been placed in circuit by the step-by-step device. After the plain part e^5 has passed the key k and the projections e^6 have passed the spring m' , another series, e^7 , of small notches act on the lever k , producing another series of actuating impulses, by which the step-by-step devices are again brought to the unison-point, thus removing the signaling-instruments at all stations from the circuit. The signaling-instruments are thus left at the unison-point immediately after a signal has been sent out from the central office, which is desirable, as it prevents possibility of any of the signals being operated by calls sent in over the same line to the main office; but as there is possibility that some of the instruments might be thrown out of the unison position in some way in the interval between two signals this final unisoning of the signals by the notches e^7 is not relied upon solely, but the instruments are also acted upon at the beginning of each transmitting operation by a number of impulses produced by the notches e^2 sufficient to bring the instruments to the unison-point if the notches e^7 should have failed to do so at the end of the last transmitting operation, or if they should have in any way been moved from the unison-point during the interval which has elapsed since the last preceding signal was transmitted. After the notches e^7 have passed the key k the projection e' comes to rest under the said key, leaving the contacts $k^2 k^3$ normally separated 100 and the contacts $k^5 k^6$ connected together, this being the only time that said contacts $k^5 k^6$ are connected.

The circuit-connections and mode of operation of the devices thus far described will be 105 best understood from the diagram Fig. 9.

The subscriber's line, grounded at its outer end, as shown at 2, and passing through the various subscribers' stations $S' S^2$, is connected with the transmitting-instruments at 110 3, by the devices commonly employed at the central office of telephone-exchanges, the said connection being made with any line on which a station is to be called. The connector 4, by which the instrument is connected with a subscriber's line, is itself connected in circuit, as 115 shown at 5, with the metallic frame-work of the instrument, including the shaft b' , disk e' , key k , and contacts $k^2 k^5$ thereof. The contact k^3 , insulated from the frame-work, as before stated, is connected by wire 6 with battery B, connected with the ground at 7, said battery being strong enough to produce the requisite actuating-currents in subscribers' 120 circuits of maximum resistance. The spring m is either connected through resistance R with one terminal of the generator G, the other terminal of which is grounded at 7, or is connected with one pole of a battery, B', the other pole of which is grounded, the said 125 battery being much smaller than the battery B and having its opposite pole connected to the spring m from that of the battery B, connected with the contact k^3 . It is very desira-

ble to provide for connecting either the generator or the battery B' with the spring m , as shown in Fig. 9. The spring m' is connected with one pole of the generator G , the other pole of which is grounded, as before stated. The contact k^6 connects with a branch, 100, grounded through the telephonic instrument T .

The operation is as follows: In the normal position the subscriber's line 23 is connected by 45 and contacts k^5 k^6 and wire 100, through the telephone T with the ground. When the disk e is rotated by the devices before described, the telephone branch 100 is first disconnected from the line at k^5 k^6 , and the notches e^2 of the disk e cause a number of impulses to be transmitted from the battery B over circuit 76 k^2 k^3 5432, rapidly actuating the step-by-step devices at the stations S' S^2 . Then the battery branch 67 is disconnected from the line at k^2 k^3 while the blank part e^3 of the disk passes the key k , and at this time the projection e^4 makes contact with the spring m , thus sending the current from the generator G and through resistance R or from the battery B' , as may be most desirable, from the said spring m to the disk e and circuit 5432. The weak current of the battery B' or the alternating-current of the generator G weakened by the resistance R will act to completely neutralize the magnetism of the step-by-step magnets at the stations and will thus release their unisoning-stops, as before stated. Then the largest notches e^4 will again actuate the key k , controlling the circuit of the battery B at k^2 k^3 , as before described, sending a number of comparatively-slow impulses of said battery, which number is determined by the position of the crank b and effect of the pin g^3 on the segment n , as before described, and after a sufficient movement to permit the maximum number of notches e^4 that will ever be required to act, the projection e^6 will cooperate with the spring m' , while the key k is held open by the blank part e^5 of the disk, thus sending the currents from the generator G over the circuit to actuate the signalling-instrument at that station where such signalling-instrument has been put in circuit by the step-by-step device.

It may in many cases be necessary or desirable to render the resistance in circuit about enough so that the battery and generator currents will act with about the same strength on the signal-instruments in the different circuits of the exchange. Such evening up of the resistance of the circuit is automatically effected by devices which will now be described, being mainly those included between the frame-plate a^2 a^3 in Fig. 2, together with certain other devices. (Best shown in Fig. 3.) These devices comprise a number of different resistance-coils which may be wound on spools indicated at r , Fig. 2, and are connected together in series, but provided with contact-points r' r^2 , &c., (see Figs. 6 and 7,) arranged in an arc on a frame-plate, a^6 . (See Fig. 2.)

The shaft t has its bearings in the plates a^3 a^6 , Fig. 2, and is in line with but disconnected from the shaft b' , as shown in Fig. 3. The said shaft t carries an arm, t' , having a yielding contact, t^2 , (see Fig. 7,) which as the said arm t' is rotated makes contact with the studs r' r^2 , interposed between the different parts of the resistance r . The said arm t' thus constitutes a switch, as will be readily understood from Fig. 9, which, when rotated in the direction of the arrow in said figure, successively cuts out the different portions of the resistance r included between the studs r' r^2 , &c. The said arm t' has a projection, t^3 , engaged by a yielding projection, t^4 , (see Figs. 3 and 8) carried by the shaft b' , so that when the said shaft is first rotated, and before the disk e is released, as before described, the said projection t^4 engages the projection t^3 and turns the switch-arm t' in the direction to cut out the various parts of the resistance r . The spring-tube of the contact t^2 (see Fig. 7) and the projection t^3 pass through a curved opening in the plate a^2 , that permits about a quarter-turn of said parts. An electro-magnet, t^5 , one coil only of which is shown in Fig. 2, is included in the circuit, and its armature t^6 is so adjusted as to be attracted when the current, which is gradually being strengthened by removal of the resistance, reaches the normal strength at which the instruments are to be operated. The armature t^6 has an arm, t^7 , which, when attracted, engages a toothed piece, t^8 , on the shaft t , and thus prevents further movement of said shaft and of the switch-arm t' the moment the magnet t^5 is energized, thus preventing further removal of resistance by the movement of said switch-arm. When the switch-arm is thus positively arrested, the projection t^4 , by which it has been turned, and which is, as before stated, made yielding, yields and permits the shaft b' to continue its rotary movement. The switch-arm t' also has a toothed arc, t^9 , which is engaged by a pawl, t^{10} , as best shown in Fig. 3, preventing the said arm from returning to its original position, toward which it is impelled by a spring, t^{11} , and at which it is arrested by a stop, t^{12} . (See Fig. 2.)

It is necessary that the current of the actuating-battery B should be on the circuit during the movement of the switch-arm t' , by which the resistance of the line is adjusted, in order that its current may be affected by said resistance, and that the magnet t^5 may be operated when the current reaches the proper strength. For this purpose the gear b^2 , or any other part carried by the shaft b' , is provided with a contact-plate, u , that co-operates with a spring, u' , to connect the battery B to line through the switch t' and resistance r during that portion of the rotation of the crank b in which the switch-arm t' accompanies it. As the magnet t^5 is in circuit during the subsequent transmission by the disk e , its armature would respond to the impulses

transmitted by said disk. This would not affect the operation of any part; but in order to prevent the rattling noise that would ensue, a stopping device, w , is provided that bears against the armature t^6 , as shown in Fig. 2, and prevents it from being retracted as the circuit is broken. It is necessary, however, for the co-operation of said armature with the notched piece t^8 that said armature should be free while the switch-arm t' is making its movement. For this purpose said stop w is connected, as shown in Fig. 3, with an arm, w' , acted upon by a cam, w^2 , on the shaft b' , which turns said stop w away from the armature t^6 just before the projection t^4 engages the projection t^3 of the switch-arm, and said cam w^2 retains the stop w away from the armature long enough to permit the arm t' to make its maximum movement.

It is necessary that the switch-arm t' should start from its original position in which all the resistance r is in circuit each time that these devices are set in operation. To insure this result, the pawl t^{10} is connected, as best shown in Fig. 3, with the rock-shaft t^{13} , having an arm, t^{14} , engaged by a pin, t^{15} , on the gear b^2 , connected with the shaft b' , before the projection t^4 reaches the projection t^3 . All these operations take place in the movement of the crank b outside of the graduated part of the dial a at some point in which it is held by the pawl c^2 after it is turned, and during this part of the movement of the arm b the disk e remains stationary, as it is not released by the pin g^3 acting on the hook g , until the crank arrives at or nearly at the graduated part of the dial.

The operation of the devices thus far described for automatically adjusting the resistance of the line will be readily understood from Figs. 3 and 9, in which latter it is shown that the subscriber's circuit 2 3 is connected with one terminal of the magnet t^5 , the other terminal of which is connected with the resistance r , while the switch-arm t' , as well as the contact-plate u , are in electrical connection with the frame-work of the machine represented at 5 in the diagram. This spring u' , that co-operates with the contact-plate u , is connected by wire 12 with the battery B , which during the entire operation of adjusting the resistance is otherwise disconnected from the frame-work of the instrument at k^2 k^3 . When the crank b is turned in the direction of the arrow, the projection t^5 first engages the arm t^{14} and trips the pawl t^{10} , permitting the switch-arm t' to be turned back to its normal position (shown in Fig. 3) by the spring t^{12} . In this position the contact t^2 of said switch-arm rests on the stud r' , and the whole of the resistance r is in circuit. Immediately after this the contact u reaches the spring u' and connects the battery B by wires 6 12 with the frame-work of the machine, including the switch-arm t' , and thence through the resistance r to the subscriber's circuit. At the same time the cam w^2 engages

the arm w' and releases the armature t^6 , which, unless the circuit is one of maximum resistance, will fall back, owing to the resistance. At the same moment the projection t^4 will engage the projection t^3 , and begin to move the switch-arm t' in the direction to cut out the successive portions of resistance between the different studs r' r^2 , &c., and when by such graded reduction of the resistance the current arrives at the desired strength the magnet t^5 will attract its armature, and will arrest the switch-arm by engagement of t^4 t^8 and prevent the further reduction of resistance. The projection t^4 will spring past the projection t^3 and the shaft b' continue its farther onward movement unaccompanied by the shaft t and switch-arm t' . Shortly after, the cam w^2 will disengage the arm w' , and the lock w will be brought up by its spring w^3 to engage the armature t^6 and prevent it responding to the currents. After this the crank b will be carried on to the number on the dial a of the station to be called, having released the disk e just before it arrives at the numbered part of the dial, so that the said disk begins its movement before the arm b comes to rest at the proper number on the dial.

If the operator should by accident carry the arm b beyond the desired number on the dial a , it cannot be turned back, and the operator might attempt to carry it wholly around again. This would be prevented by the stop g^4 g^5 , and the crank b when released would fall back and be held by the pawl c^2 opposite the zero-point on the dial. This would cause the step-by-step device of the signaling-instrument to be turned wholly around before the generator-current was applied by the spring m' , and consequently no station-signal would be in circuit and no false alarm given. The operator would consequently have to wait until the disk e had finished its rotation and thus raised the stop-hook g^4 , so that the crank b could be again operated and this time stopped at the proper point.

In actual practice it does not require over ten seconds for a complete rotation of the disk e , so that but little time is thus lost.

Several of the devices herein described are not absolutely essential to the operation of the transmitter, but all contribute to render the instrument convenient and efficient in operation, and it is to be understood that the omission of non-essential devices or variations in their construction, not changing the essential mode of operation, is not a substantial departure from the invention herein shown and described.

The shaft b' is the actuating and controlling shaft for the entire instrument, and the disk e is the circuit-controlling part, and its various notches and projections constitute the signaling-surface, which, in conjunction with the contact springs and keys co-operating with it, determine the character of the current and of the interruptions of the current

by which the required effect is produced on the signal-receiving instruments, and it is obvious that the mechanical construction of these parts might be varied and equivalent devices employed without departing from the invention.

I claim—

1. The controlling-shaft movable to and held in different positions, combined with a current-interrupter controlled by the said shaft, and a lock for said current-interrupter and a releasing-projection therefor connected with the said shaft, whereby the said interrupter is released and produces a number of electric impulses dependent on the point at which the said shaft has been stopped, substantially as described.

2. The main-line and two branch circuits containing sources of different kinds of electric currents—as, for instance, a battery and magneto-generator—combined with a transmitting-instrument comprising a movable signaling-surface having a definite cycle of movement, the same at each operation, and an actuator therefor, and circuit-controlling contacts operated thereby during said continuous movement, controlling the connection of said branches with the main line, substantially as and for the purpose described.

3. The main-line and three branch circuits, one containing a battery, one a magneto-generator, and the third containing a source of currents of opposite polarity to that of the said battery, combined with a transmitting-instrument comprising a movable signaling-surface having a definite cycle of movement, the same at each operation, and actuator therefor and circuit-controlling contacts operated thereby, by which the said branches are all connected to line each at different times during a single operation of said signaling-surface, substantially as and for the purpose described.

4. The actuating-shaft and wheel having a signaling-surface loose thereon and actuating-spring connecting said shaft and wheel, combined with a stop for said wheel released by said actuating-shaft and a second stop connected with said wheel-stop and operated thereby, the second stop being arranged to arrest the actuating-shaft, except when the first is engaged with the said wheel, substantially as described.

5. The actuating-shaft and transmitting-wheel loose thereon, combined with an actuating-spring connecting the said shaft and wheel, an arm loose on said shaft, and stops co-operating with said arm on said wheel, and a projection co-operating with said arm connected with said actuating-shaft, substantially as and for the purpose described.

6. The actuating-shaft and disk fixed thereon, having a portion of its periphery provided with ratchet-teeth, combined with a pawl to

engage said teeth, a circuit-controlling wheel 65 loose on said shaft, and an actuating-spring connecting said shaft and wheel, and a stop for said wheel operated to release the wheel by the movement of the shaft, substantially as described.

7. The actuating-shaft movable to and held in different positions, combined with a circuit-controlling wheel having a signaling-surface and electric contacts controlled thereby, a segment connected with said wheel, and a 75 projection co-operating with the said segment connected with the actuating-shaft, whereby the said segment is moved to prevent a portion of the signaling-surface from operating the contacts, substantially as described.

8. The combination of the main circuit and generator of electricity therein, with resistance in said circuit and contact-points between different portions of said resistance, 85 a switch movable over the said contact-points, and an electro-magnet included in said circuit, and an armature therefor which engages and arrests the said switch when the attraction of the magnet overcomes the retractor of the armature, substantially as described.

9. The combination of the actuating-shaft, with a movable switch engaged by said shaft, and an electro-magnet and its armature that 95 arrests the said switch, a lock that retains the said switch in the position to which it has been moved, and a releasing device for said lock operated by said shaft before the latter engages the said switch, substantially as and 100 for the purpose described.

10. The combination of the actuating-shaft with a movable switch engaged by said shaft, and an electro-magnet and its armature that arrests the said switch, a lock that holds the 105 said armature up to its magnet, and an actuator for said lock on said shaft by which the armature is released while the switch is engaged by the shaft, substantially as and for the purpose described.

11. The main circuit and transmitting instrument provided with a circuit-controlling wheel and electric contacts operated thereby, combined with a branch circuit containing a source of electricity which is connected to 115 said main circuit during the movement of said wheel, and another branch containing a telephone which is connected to said main circuit by the wheel-controlled contacts when said wheel is arrested in its normal position, 120 substantially as described.

In testimony whereof I have signed my name to this specification in the presence of two subscribing witnesses.

WALTER J. DUDLEY.
